CLAIM

The ornamental design for a light-blocking window element with extension, as shown and described.

DESCRIPTION

FIG. 1 is a front perspective view of the first embodiment of a light-blocking window strip element with extension showing the new design;

FIG. 2 is a rear perspective view thereof;

FIG. 3 is a right side view thereof;

FIG. 4 is a left side view thereof;

FIG. 5 is a top view thereof, a bottom view being a mirror thereof;

FIG. 6 is a front side view thereof;

FIG. 7 is a rear side view thereof;

FIG. 8 is a front perspective view thereof, showing an alternate position;

FIG. 9 is a rear perspective view thereof, showing an alternate position;

FIG. 10 is a top view thereof, showing an alternate position, the bottom view being a mirror thereof;

FIG. 11 is a front perspective view of the second embodiment of a light-blocking window strip element with extension;

FIG. 12 is a rear perspective view thereof;

FIG. 13 is a right side view thereof;

FIG. 14 is a left side view thereof;

FIG. 15 is a top view thereof, the bottom view being a mirror image thereof;

FIG. 16 is a front side view thereof;

FIG. 17 is a rear side view thereof;

FIG. 18 is a front perspective view thereof, showing an alternate position;

FIG. 19 is a rear perspective view thereof, showing an alternate position; and,

FIG. 20 is a top view thereof, showing an alternate position, the bottom view being a mirror image thereof;

The break lines shown in FIGS. 1-9, 11-14, and 16-20 symbolize breaks in the length of the article in which the claimed design is embodied. The appearance of any portion of the article between the break lines forms no part of the claimed design.

1 Claim, 8 Drawing Sheets
